UNITED STATES PATENT OFFICE.

OTTO RITTER, OF ST. LOUIS, MISSOURI, ASSIGNOR OF ONE-HALF TO MEYER & HOFMAN, OF SAME PLACE.

WORT AND YEAST AERATOR FOR BEER-VATS.

SPECIFICATION forming part of Letters Patent No. 466,310, dated December 29, 1891.

Application filed August 4, 1891. Serial No. 401,658. (No model.)

To all whom it may concern:

Be it known that I, OTTO RITTER, of the city of St. Louis, in the State of Missouri, have invented a certain new and useful Improvement in Wort and Yeast Aerators for Beer-Vats, of which the following is a full, clear, and exact description, reference being had to the accompanying drawings, forming part of this specification.

10 This apparatus is constructed and arranged to effect the rapid and thorough amalgamation, aeration, and purification of wort and yeast in brewers' vats, &c.; and the invention consists in features of novelty hereinafter 15 fully described, and pointed out in the claims.

Figure I is a detail view of the aerator and shows the coupling for the air-hose, the air-filter, the bulb-casing of which filter forms a handle or hold for the operator, by which he 20 directs the instrument. It also shows the inception filtered air-chamber, the supply air-tube, and the compound aerating-bulb; and Fig. II is a vertical section of a brewer's fermenting-vat and shows the yeast and wort 25 aerator in active operation therein.

Referring to the drawings, 1 represents a brewer's vat resting on its sleepers 2, and 3 is the wort with its quota of yeast deposited in said vat and in the process of fermentation. 30 4 represents the usual circlet temperator that is suspended in the wort within the vat, and 5 are the refrigerator-pipes that conduct a current of cold air to, through, and from said temperator.

35 The construction and operation of the aerating apparatus are as follows: 6 represents a pneumatic hose, which may be of rubber or any other suitable material, and which gets its supply of air from any suitable pneumatic 40 force-pump worked by power or hand. The said hose fits over the corrugated periphery 7 of the metal coupling-tube joint 8, to which it is tightly held by the binding wire or cord 9, and the terminal flange 10 of said tube- 45 joint fits and is thus held within the flange 11 of the screw-coupler 12, whose inner screw 13 engages on the rear peripheral screw 14 of the coupling-tube plug 15, whose forward peripheral screw 16 engages in the internal 50 screw 17 of the initial flange 18 of the tubulous bulb 19, which incloses the air-filter 20. The said filter-bulb is filled with sterilized cotton 21 or other suitable air filtrant

as an antiseptic to cleanse the air that passes through it of all noxious ingredients. 22 represents a perforate disk that fits against the advance screw-threaded end 23 of said tubulous filter-bulb, on which peripheral screw is seated the internal screw 24 of the rear flange 25 of the secondary tubulous bulb 26, which incloses the pure-air chamber 27, which is supplied with cleansed air through the perforations in said disk 22 direct from the said air-filter. The internal screw 28 of the forward attachment flange 29 of said secondary bulb 65 engages on the peripheral screw 30 of the joint-pipe 31, which pipe has a screw-tight attachment *via* the elbow-joint pipe 32 with the pendent pipe 33, which pendent pipe has a screw-tight connection 34 with the head 35 of the initial tubular plug 36. 70

37 represents the secondary aerating tubular plug, within the internal screw 38 of which the peripheral screw 39 of the initial plug engages to effect a screw-tight-joint connection 75 of said two plugs. 40 represents the expansion air-chamber within said initial plug, into which the forced air is driven from the pendent pipe 33, and from which chamber the air is concentratively driven through the converging tube 41, the blow-pipe 42, and concave outlet 43 into and through the initial yeast and wort mixing and aerating concentrating-tube 44 within said secondary aerating-plug 37. The rapid forced draft thus provided produces a powerful suction of the wort and yeast in the vat through the open ports 45 in the upper part of said aerating-tube, and together the wort, yeast, and rapid air-current are forcibly concentrated in said 80 converging tube 44, thus intimately mixing said wort and yeast and aerating the same by said concentrative process, and then violently ejecting the aeriferous compound into the expansive bulb 46, from which it is violently ejected through the perforations 47 of its rose end 48. The said action forcibly drives the aerated compound against the inner surface of the rose-terminal of said bulb, and thus still more intimately and forcibly 90 conducting to the aeration and effervescence of the fermenting compound, both within said bulb, and as it is forcibly ejected into the vat through the perforations or open ports 47 the whole contents of the vat are soon aerated 95 and in a high state of effervescence. The up- 100 105

per end of said bulb-terminal section 46 is provided with an internal screw 49, that is screw-seated on the peripheral screw 50 of the secondary plug to hold said bulb in its

5 attachment to said plug.

The operation of the device has necessarily been mostly portrayed in this description, but may be more clearly understood by the following brief capitulation and addenda.

- 10 The tubulous filter-bulb 19 having been filled with sterilized—that is, purified—cotton and the various parts of the apparatus described before securely screw-seated together and attached to the pneumatic hose, which is worked by a force-pump the operator grasps the said tubulous filter-bulb, which also constitutes a handle, and inserts the aerating-bulb and the pipe-stem 33, that carries it in the wort and yeast in the beer-vat. As the air is forced rap-
- 15 idly through the apparatus, being cleansed of all noxious impurities as it passes through the before-described pneumatic filter, it whirls (with the first break in its current since it left the filter) into the expansion-chamber 40, from
- 20 which it darts through the converging contractile tube 41 *via* the blow-pipe 42 and concave expansion-outlet 43 into the aerating concentrating-tube 44, generating a strong suction-draft through the open ports 45, draw-
- 25 ing a rapid current of the wort and yeast in the vat through said ports into and through said aerating concentrating-tube, aerating it on its way and expelling it with great force and thrashing it against the perforate rose expansion-bulb 46 and through the perforations 47
- 30 into the main body of wort and yeast in the vat, which it rapidly aerates and ferments. The operator meantime moves the aerating-bulb around so that it visits in its journey
- 35 all parts of the vat, so as to make the aeration and fermentation of the contents much more rapid than by the old process, repeated trials of the device having proved a saving of two days in the operation, with a more
- 40 lively and effective fermentation.

I claim as my invention—

1. In a wort and yeast aerator for beer-vats, the combination of the pneumatic hose 6, the air-filter into which said hose discharges, the
- 50 aerating and mixing bulb 46, having the tubular plug 37, the said plug being provided with the open ports 45, through which the yeast and wort are drawn by suction within said bulb for mixture and aeration, and the air-tube
- 55 that connects said filter to said bulb, substantially as and for the purpose set forth.
2. In a wort and yeast aerator for beer-vats, the combination of the pneumatic hose 6, arranged for connection to a pneumatic force-
- 60 pump, the tubulous bulb 19, to which said hose is connected, the said bulb containing the air-filter chamber, the sterilized cotton that constitutes the filtrant in said chamber, the air-tube that receives and dispenses said
- 65 forced filtered air, and the compound aerating and mixing bulb into and through which said forced draft is delivered, said bulb being

provided with entrance-ports through which the wort and yeast in said vat are drawn for mixture, substantially as and for the purpose set forth.

3. In a wort and yeast aerator for beer-vats, the combination of the pneumatic hose arranged for connection to a force-pump, the tubulous bulb 19, to which said hose is connected, the said bulb containing the air-filter chamber 20, the filtrant in said chamber, the perforate disk 22 at the forward end of said chamber, the pure-air chamber 27, the air-tube that receives and dispenses said forced filtered air, and the compound aerating and mixing bulb into and through which said filtered forced air with the wort and yeast in said vat are churned and aerated, substantially as and for the purpose set forth.

4. In a wort and yeast aerator for beer-vats, the combination of the pneumatic hose arranged for connection to a force-pump, the tubulous bulb 19, to which said hose is connected, the air-filter chamber 20, contained in said bulb, the filtrant in said chamber, the perforate disk 22 at the forward end of said chamber, the secondary bulb 26, the pure forced air chamber 27 within said secondary bulb, the air-tube that receives and dispenses said forced filtered air, the initial plug 36 of the aerating and mixing bulb, said initial plug containing the expansive air-chamber 40, the converging tube 41, the blow-pipe 42, and the expanding concave outlet 43, and the perforated compound aerating and mixing bulb into which said initial tubulous plug 36 is inserted, substantially as and for the purpose set forth.

5. In a wort and yeast aerator for beer-vats, the combination of the pneumatic hose arranged for connection to a force-pump, the tubulous bulb 19, to which said hose is connected, the air-filter chamber 20 and filtrant 21, contained in said bulb, the perforate disk 22 at the forward end of said chamber, the pure forced air chamber 27 and secondary bulb 26, in which said air-chamber is contained, the air-tube that receives and dispenses said forced filtered air, the initial tubulous plug 36 of the aerating and mixing bulb, the said plug containing the expansive chamber 40, the concentrating blow-pipe tubes 41 and 42, and the expansion-outlet 43, the secondary tubulous plug 37, provided with the open ports 45, through which the wort and yeast enter for mixture and aeration, the aerating concentrating-tube 44, and the expansion-bulb 46, in which said secondary bulb is seated and in which said wort and yeast are churned and aerated, the said bulb being provided with rose-perforations 47, through which the aerated wort and yeast are forcibly blown into the contents of the beer-vat, substantially as and for the purpose set forth.

OTTO RITTER.
